G. W. BORTON

SCREEN BAR FOR CRUSHING MACHINERY

Filed Dec. 15, 1926

INVENTOR:
George W. Borton,
by Murray G. Boyer
Attorney.

Patented Apr. 12, 1927.

UNITED STATES PATENT OFFICE.

GEORGE W. BORTON, OF PHILADELPHIA, PENNSYLVANIA, ASSIGNOR TO PENNSYLVANIA CRUSHER COMPANY, OF NEW YORK, N. Y., A CORPORATION OF NEW YORK.

SCREEN BAR FOR CRUSHING MACHINERY.

Application filed December 15, 1926. Serial No. 154,916.

My invention relates to crushing machinery employed in reducing coal, ore, stone, and the like, more particularly those familiarly known as hammer crushers, and one object of my invention is to provide an improved form of screen bar employed in making up the discharge grid or grate of structures of this type; such grid or grate being disposed substantially concentric with respect to the path of the hammer members which effect the breaking or crushing of the material operated upon by beating it against the edges of the bars making up such grid or grate.

15 A further object of my invention is to provide a self-spacing bar; such spacing means being formed integral with the bar or not, as may be desired.

20 And a still further object of my invention is to provide a reversible bar having spacing means which will be disposed in substantially the same relation no matter what the position of the bar may be in the seats provided for the ends of the same; 25 such seats being in the form of semicircular grooves in a frame or cage which may be pivotally mounted in the side walls of the crushing structure.

These and other features of my invention 30 are more fully described hereinafter; reference being had to the accompanying drawings, in which:

Figure 1, is a cross sectional elevation, more or less diagrammatic, of one form of 35 crushing machinery in which my improved screen bar may be employed.

Fig. 2, is a perspective view of one of the screen bars shown in Fig. 1.

Fig. 3, is an end view of another form of 40 screen bar.

Figs. 4 and 5, are sectional views illustrating other forms of screen bars within the scope of my invention, and

45 Figs. 6, 7, 8 and 9, are diagrammatic views illustrating the position of my improved bars in use; such views showing clearly their availability for reversal to increase their wearing life.

The improved screen bar forming the subject of my invention is particularly available for use with hammer crushers, and in Fig. 1, I have illustrated, more or less diagrammatically, a crushing machine of this type, having the usual cage or frame 1,

55 pivotally mounted at 2, and providing grooves 3, forming seats for the reception of the ends of bars 4, which make up the grid or grate constituting the cage, and against which the crushing or breaking action takes place under the action of hammers 5.

These hammers may be pivotally mounted on rods 6, carried by disks 7, supported by a shaft 8, and constitute the rotor element of the crushing machine. The frame or cage 1, 65 carrying the bars 4, is pivotally mounted in the usual manner so as to permit adjustment of the grate or grid formed by said bars 4, with respect to the path of the hammers.

A bar of the preferred construction is 70 shown in Fig. 2, and comprises a section of steel, of material length, rectangular or substantially so in cross section, having projections 4^a, which may be integral with the body of the bar; such projections being disposed inwardly a slight distance with respect to the active edges of the bars. The projections 4^a are preferably beveled in two directions with respect to the side faces of the bars so that when disposed in proper 75 relation to the rotor element to form the screen or grate of the crushing structure, one of the inwardly disposed surfaces 4^b, of each of such projections will be in contact throughout its entire area with the near face 80 of an adjacent bar, and such contacting surfaces 4^b will lie in planes substantially parallel to radial lines passing through adjacent contacting bars.

By preference, one face only of each of 85 the bars is provided with these spacing projections, and the extent their lateral projection with respect to said bars determines the distance between the several bars in the formation of the cage or screen; which distance 90 may differ for different material undergoing crushing. In the preferred construction of my improved screen bars, these spacing projections are integral, as shown in Figs. 2, 6, 7, et seq.

I may, however, provide these spacing projections upon both sides of the bars, as shown in Fig. 3, and in either instance they may be separate pieces suitably secured to the bars; Figs. 4 and 5, showing constructions within the scope of my invention, in which the spacing projections are separate pieces, indicated at 44, and are secured to

the bars by means of rivets 10. Other fastening means may be employed without departing from my invention.

In use, the forward edges of the bars 4, are subject to excessive wear, and by making these bars rectangular in cross section it is possible to utilize all four edges for crushing effect as they are successively worn; the bars being capable of reversal as well as 10 being turned end for end.

In Figs. 6, 7, 8 and 9, I have illustrated, diagrammatically, the manner of using my improved bar so that full advantages may be taken of its reversibility in order that increased wear may be secured before replacement. Fig. 6, shows a set of bars in the first position before any wear occurs; Fig. 7, shows the position of bars after being turned end for end, with the edge opposite 15 the worn edge in service; Fig. 8, shows the bars reversed, with the two worn edges at the outer peripheral margin of the grid or grate, and Fig. 9, shows the bars in the last position of use before renewal becomes 20 necessary.

In all instances, the projections are beveled in the manner indicated; the beveled surfaces being tangent to the plane of the side walls of the bars, with the contacting 25 portions of such projections lying in planes substantially parallel with radial lines passing through adjacent bars of the semi-cir-

cular grate or screen from the axis of rotation.

I claim:

1. A screen bar substantially rectangular in cross section, having a plurality of spacing lugs disposed inwardly with respect to the edge of the bar and projecting at right angles with respect to the longitudinal axis of 40 the bar; each lug being provided with flat contacting faces disposed each at an angle to the other.

2. A screen bar rectangular in cross section, having a plurality of integral spacing 45 lugs disposed on one side of said bar and set inwardly with respect to the edges of the bar; each lug being provided with flat contacting faces disposed each at an angle to the other.

3. A screen bar rectangular in cross section, having a plurality of spacing lugs projecting at right angles from a broad surface of the same and positioned inwardly with respect to the marginal edges of said bars, 55 and each of said spacing lugs having a plurality of outwardly beveled bearing surfaces meeting in a plane intermediate the working edges of the bar whereby flat contacting faces disposed at an angle to each other are 60 provided.

In witness whereof I have signed this specification.

GEORGE W. BORTON.
